UNITED STATES PATENT OFFICE.

FRED R. GOOLMAN, OF BINGHAMTON, NEW YORK, ASSIGNOR TO HARRIS PLAYER PIANO COMPANY, OF BINGHAMTON, NEW YORK, A CORPORATION OF NEW YORK.

SELECTIVE PIANO-PLAYER MECHANISM.

1,090,706.

Specification of Letters Patent. Patented Mar. 17, 1914.

Application filed December 2, 1912. Serial No. 734,536.

To all whom it may concern:

Be it known that I, FRED R. GOOLMAN, a citizen of the United States, residing at Binghamton, in the county of Broome and 5 State of New York, have invented certain new and useful Improvements in Selective Piano-Player Mechanism, of which the following is a specification.

The present invention relates to certain 10 new and useful improvements in mechanical piano player mechanisms, and has for its primary object to provide a mechanism of this character which embodies novel features of construction whereby the character 15 of music being played can be instantly changed without the necessity of manually removing or replacing the perforated music sheet in the usual manner.

A further object of the invention is to 20 provide a device of this character which is comparatively simple and inexpensive in its construction, which is positive and reliable in its operation, which gives a considerable latitude in the selection of music, 25 and which requires but little care and attention on the part of the operator.

With these and other objects in view, the invention consists in certain novel combinations and arrangements of the parts as 30 will more fully appear as the description proceeds, the novel features thereof being pointed out in the appended claims.

For a full understanding of the invention, reference is to be had to the following 35 description and accompanying drawings, in which:—

Figure 1 is a top plan view of two of the player units. Fig. 2 is a transverse sectional view of the same. Fig. 3 is a longitudinal 40 section taken at a point between two of the units, showing one of said units in elevation. Fig. 4 is a sectional elevation showing the connection between the duct bridge and the vacuum pipes. Fig. 5 is a detail elevation 45 illustrating the position of the various parts when the unit is out of action, and Fig. 6 is a diagrammatic view of the means for controlling the various player units. Fig. 7 is a detail view showing the spring connection with the rock shaft.

Corresponding and like parts are referred to in the following description and indicated in all the views of the drawings by the same reference characters.

55 In carrying out the present invention, a

series of duplicate and independent player units are provided, each player unit including its own music sheet and duct bridge, any selected one of the player units being adapted to be brought into action and the 60 remaining player units simultaneously rendered inoperative.

Specifically describing the present embodiment of the invention, the numeral 1 designates the main frame upon which the 65 mechanism is mounted. The various independent player units are each mounted upon a small frame 2 which is adapted to be secured to the main frame 1. Suitably mounted upon each of the small frames 2 of the 70 various individual player units is a duct bridge 3; and leading from the several duct bridges to some suitable form of playing mechanism are the usual tubes 4. Journaled upon one side of each of the duct bridges 3 is a flanged guide roller 5, and journaled upon the opposite side of each of the duct bridges is a flanged feed roller 6, the perforated music sheets 7 being adapted to pass over the duct bridges 3 and the flanged 80 rollers 5 and 6, and to be positively drawn across the duct bridges by rotation of the feed rollers 6. A presser roller 8 bears 75 yieldingly against each of the feed rollers 6 so as to hold the music sheet 7 in a frictional engagement with the feed roller and prevent any possibility of an improper feed of the sheet music due to slipping of the feed roller with respect thereto. The presser 85 rollers 8 are shown as journaled between the swinging arms 9, the said swinging arms 9 being connected by a transverse rod 10 which is engaged by a spring 11. This spring 11 forces the presser roller yieldingly 90 toward the feed roller so as to grip the sheet music securely between the rollers and insure a proper feeding of the sheet music when the feed roller is driven. The sheet music 7 may be of any suitable or approved 95 construction, and in the present instance the ends thereof are connected so as to form a continuous web, a flanged spool 12 resting loosely in the lower end of the web and being supported thereby so as to retain the pendent portion of the web in a slightly 100 stretched condition and insure a proper feeding thereof.

Arranged opposite the duct bridge 3 of each of the independent player units is a duct-closing damper or valve member 13, 110

the said valves being shown as carried by swinging arms 14 which are pivoted upon the standards 15. An arm 16 projects longitudinally from one end of each of the duct closing valves 13 and is connected by a link 17 to one end of a lever 18 which is pivoted between its ends at 19, the opposite end of the said lever being engaged by a push rod or plunger 20, as will be hereinafter more fully described. The various duct closing valves or dampers 13 normally drop by the action of gravity upon the respective duct bridges so as to close the ducts and render the player units inoperative. However, when one of the push rods 20 is operated so as to swing the respective lever 18 about its pivot 19, the link 17 will be pushed upward so as to move the duct closing valve 13 away from the duct bridge and into an inoperative position.

A main standard 21 is provided for each of the individual player frames 2, the shafts 22 upon which the various feed rollers 6 are mounted being extended beyond the ends of the feed rollers and journaled in the said main standards. A drive wheel 23 is loose upon each of the shafts 22, the said drive wheels being shown in the present instance as retained against longitudinal movement upon the said shafts, by means of the fingers 24 which are carried by the main standards and project loosely into annular grooves 25 in the hub portions of the drive wheels. The various drive wheels 23 are adapted to be driven continuously in some suitable manner as by means of the chain 26, and a clutch mechanism 27 is provided for each of the drive wheels whereby any selected one of the drive wheels can be locked with the respective shaft 22 of the feed roller 6. The various clutch devices 27 are controlled by the levers 28 which are pivoted at intermediate points in their length as indicated at 29 upon the lower brackets 30 which project from the main standards 21. Springs 31 are connected to the upper arms of the levers 28 and normally tend to swing the said levers to throw the clutch members 27 into inoperative positions.

An upper bracket 32 projects from each of the main standards 21 over the lower bracket 30, and mounted upon each of the upper brackets is a detent or pawl 33 which is adapted to engage the upper end of the clutch controlling lever 28 to hold the said lever against the action of the spring 31 and retain the clutch mechanism 27 in an operative position. Each of the detents 33 is provided with an upwardly projecting arm 34 which is connected by a link 35 to an upwardly projecting arm 36 on a rock shaft 37. This rock shaft 37 is common to all of the various independent player units and is journaled in the outer ends of the upper brackets 32, so that all of the detents or

pawls 33 are locked together in such a manner as to be simultaneously operated. A spring 37 which is connected to an arm 38 of the rock shaft normally tends to rotate the rock shaft to hold the detents 33 yielding in operative position. 70

A pneumatic 38 is mounted upon each of the main standards 21, the various pneumatics being provided with perforated ears 39 which receive the outer ends of rods 40 and are adapted to abut against the shoulders 41 upon the said rods to produce a thrust or longitudinal movement thereof when the pneumatic is operated. The opposite ends of the rods 40 are connected to the upper ends of the clutch controlling levers 28 so that when one of the pneumatics 38 is operated, the thrust upon the rod 40 produced thereby will serve to move the clutch controlling lever 28 and bring the clutch mechanism 27 into an operative position 85 so that the feed roller 6 of the player unit will be operated. In this connection, it will be observed that the clutch controlling lever 28 is provided at an intermediate point in the length thereof with a lateral arm 28a which is connected to the push rod or link 20, so that the lever 18 is operated to lift the duct closing valve 13 at the same time that the clutch mechanism 27 is thrown 95 into operative position.

The operation of the pneumatic 38 produces a greater movement of the clutch controlling lever 28 than is required to render the clutch mechanism 27 operative and lift the duct closing valve 13. This additional or surplus movement of the clutch controlling lever 28 brings the same into engagement with a downwardly projecting finger 42 upon the rock shaft 37 so as to produce a rotary movement of the said rock shaft and simultaneously lift all of the detents 33 into an inoperative position. Any one of the clutch controlling levers 28 which may previously have been locked in an operative position by engagement with one of the detents 33 will then be released, so as to shut off or render inoperative all of the player units, with the exception of that one which has been thrown into action by the operation of its pneumatic 38. The action of the pneumatic 38 is only momentary and as soon as the pneumatic is rendered inoperative, the spring 31 will draw the upper end of the clutch controlling lever 28 back 115 until the movement of the lever is arrested by engagement with the detent 33. It will thus be obvious that when any one of the pneumatics 38 is operated, the particular player unit of which the pneumatic forms 120 a part will be instantly thrown into action and all of the other player units rendered inoperative. 125

The numeral 43 designates the main vacuum pipe from which a series of branch pipes 130

43^a lead to the respective pneumatics 38. A valve 44 is interposed in the length of each of the branch pipes 43^a, each of the said valves being shown as having an operative connection with the armature 45 of an electro-magnet 46 so as to be automatically opened when the electro-magnet is energized. Any suitable means may be provided for energizing selected ones of the 10 electro-magnets 46. A battery 48 or other suitable source of electric supply is provided, one of the terminals of the battery being connected by a wire 49 to a conductor 50 while the opposite terminal of the battery is connected by a wire 51 to a conductor 52. One of the terminals of each of the electro-magnets 46 is connected by a wire 53 to a conductor 52, the opposite terminal of each of the electro-magnets being connected by a wire 54 to one of the terminals of a suitable circuit closer 55. The other terminals of the circuit closers 55 are connected by the wires 56 to the conductor 50. It will thus be obvious that when any selected one of the circuit closers 55 is operated, the corresponding electro-magnet 46 will be energized so as to open the valve 44 and momentarily actuate the pneumatic 38 of the corresponding player unit. As 20 has been previously described, this particular player unit will be thereby placed in operation and all of the remaining player units simultaneously shut off or rendered inoperative. One of the circuit closers 55 would be provided for each of the independent player units, and it will be obvious that the number of player units employed may be multiplied indefinitely, according to the number of musical selections which 25 it is necessary or desirable to have available for instantaneous production. The character of the music or the title of the piece adapted to be played by each of the independent player units might be set forth in tabular form by suitable characters arranged opposite the various circuit closers 55, as indicated at 56.

This player piano mechanism is well adapted for use as an accompaniment in connection with moving pictures, since the character of the musical composition being played can be instantly changed at any time, and by having a suitable number of independent player units, a large variety of musical compositions are rendered available to the operator. By operating selected ones of the circuit closers 55, any one of the compositions can be produced, and the character of the music can be instantly changed as often as may be required by the changing character of the moving picture film. A switchboard containing the various circuit closers 55 could be very readily located adjacent the moving picture machine so as to be manipulated by the moving picture op-

erator. It will also be obvious that the mechanism is well adapted for use in connection with coin controlled devices, since it enables the operator to select any desired piece, and to change the pieces at any time and as often as may be desired.

Having thus described the invention, what I claim as new and desire to secure by Letters Patent, is:—

1. A piano player mechanism including means for maintaining a plurality of independent note sheets in operative position at all times, and selective mechanism comprising means for causing any one of the note sheets to be instantly started to play and to simultaneously and instantly arrest the play of any other note sheet in action. 75

2. A piano player mechanism including mechanical means for simultaneously maintaining a plurality of independent note sheets in operative position at all times, selective means for causing any one of the note sheets to be instantly played, and means actuated by the said selective means for instantly stopping the playing of any other note sheet in action. 85

3. A piano player mechanism including a series of independent player units each of which has its own note sheet and duct bridge, selective means for causing any one of the note sheets to be instantly played, and means actuated by the said selective means for instantly stopping the playing of any other note sheet in action. 95

4. A piano player mechanism including a series of independent player units each of which is provided with its own note sheet and duct bridge, a duct closing valve for each of the duct bridges, selective means for bringing any one of the player units into action and opening the duct closing bridge thereof, and means actuated by the said selective means for automatically shutting off any of the other player units which may have been in action and closing the duct closing valves thereof. 100

5. A piano player mechanism including a series of independent player units maintained in operative position at all times, independent driving elements for each of the units, clutch means controlling the driving elements, selective means controlling the clutch means for bringing any selected one of the player units instantly into action, and means actuated by the said selective means for automatically and simultaneously shutting off any of the other player units which may have previously been in action. 115

6. A piano player mechanism including a series of independent player units each of which is provided with its own note sheet and duct bridge, duct closing valves for the duct bridges, independent driving elements for each of the units, clutch means controlling the driving elements, selective means 120

controlling the clutch means for bringing any selected one of the player units instantly into action, and means actuated by the said selective means for automatically and simultaneously shutting off any of the other player units which may have previously been in action. 130

for operating the clutch of any unit and simultaneously operating the duct closing valve thereof, and means actuated by the said selective means for automatically shutting off any of the player units which may have been previously in action and closing the duct closing valves thereof.

7. A piano player mechanism including a series of independent player units each of which is formed with a duct bridge and an endless note sheet which is always in operative position upon the duct bridge, selective means for instantly bringing any one of the note sheets into action regardless of their position on their respective duct bridges, and means actuated by the said selective means for simultaneously shutting off any of the other units at any point in their playing which may have previously been in action.

8. A piano player mechanism including a series of independent player units each of which has its own duct bridge and an endless note sheet which is always in operative position thereon, a duct closing valve for the duct bridge of each player unit, independent driving elements for each of the units, clutch means controlling the driving elements, selective means for actuating the clutch means to bring any one of the player units instantly into action and opening the duct closing valve thereof, and means actuated by the said selective means for simultaneously shutting off the other player units and closing the duct closing valves thereof.

9. A piano player mechanism including a series of independent player units in operative position at all times each of which is provided with its own music sheet and duct bridge, a duct closing valve for each of the duct bridges, independent driving elements for the units, clutches controlling the driving elements, and levers having operative connections with both the clutches and the duct closing valves so that any selected one of the clutches can be thrown into operative position and the corresponding duct closing valve simultaneously opened.

10. A piano player mechanism including a series of independent player units, independent driving elements for each of the units, clutches for controlling the driving elements, levers for the clutches, detents adapted to engage the levers to hold the clutches in operative position, and means for releasing all of the detents when any selected one of the levers is manipulated to throw a particular one of the player units into action.

60 11. A piano player mechanism including a series of independent player units, independent driving elements for each of the units, clutches controlling the driving elements, levers having operative connections

with the clutches, detents for engaging the levers to hold the clutches in operative positions, a rock shaft, an operative connection between the rock shaft and the various detents, and means whereby the rock shaft is actuated when any selected one of the levers is moved to bring one of the player units into action, the movement of the rock shaft serving to release all of the other detents.

12. A piano player mechanism including a series of independent player units, independent driving elements for the units, clutch means for controlling the driving elements, levers having operative connections with the clutch means, detents for engaging the levers to hold the same in operative position, a rock shaft provided with fingers adapted to be engaged by the levers when the latter are actuated, and an operative connection between the rock shaft and the detents whereby all of the detents are moved into inoperative position when a selected one of the levers is operated to bring one of the player units into action.

13. A piano player mechanism including a series of independent player units, independent driving elements for the units, normally inoperative clutch means for controlling the driving elements, levers having operative connections with the clutch means, detents for engaging the levers to hold the same in operative position, independent pneumatics for the player units, operative connections between the various pneumatics and the clutch controlling levers, and means actuated by the operating of any one of the pneumatics for releasing the clutch controlling levers of the other player units.

14. A piano player mechanism including a series of independent player units, independent driving elements for the pneumatics, normally inoperative clutch means for controlling the driving elements, levers having operative connections with the clutch means, detents for engaging the levers to hold the same in operative position, independent pneumatics for the various player units, operative connections between the various pneumatics and the clutch controlling levers, a rock shaft common to all of the player units and having an operative connection with the various detents, and means whereby the rock shaft is moved when any one of the levers is operated by its pneumatic, the movement of the lever serving to move the detents to release the remaining levers.

15. A piano player mechanism including a series of independent player units each of which is provided with its own music sheet and duct bridge, normally closed duct closing valves for the duct bridges, independent pneumatics for the player units, and means actuated by each of the pneumatics for

throwing the respective player unit into action and opening the duct closing valve thereof.

16. A piano player mechanism including 5 a series of independent player units each of which is provided with its own music sheet and duct bridge, normally closed duct closing valves for the duct bridges, independent pneumatics for the various player units, 10 means actuated by each of the pneumatics for throwing the corresponding player unit into action and opening the duct closing valve thereof, and means also actuated by each of the pneumatics for rendering all of 15 the other player units inoperative.

17. A piano player mechanism including a series of independent player units each of which is provided with its own music sheet and duct bridge, independent driving 20 elements for the units, clutches controlling the driving elements, levers having operative connections with the clutches, normally closed duct closing valves for the duct bridges, operative connections between the 25 clutch controlling levers and the duct closing valves, means for moving any one of the levers to close the clutch of the player unit and open the duct closing valve thereof, and means actuated by the movement of the said 30 lever for rendering all of the remaining player units inoperative.

18. A piano player mechanism including a series of independent player units each of which is provided with its own music 35 sheet and duct bridge, normally closed duct closing valves for the duct bridges, independent driving elements for the player units, clutches controlling the driving elements, levers having operative connections 40 with the clutch means, operative connections between the clutch controlling levers and the duct closing valves, detents for engaging the levers to hold the clutches in operative position, a rock shaft, an operative connection 45 between the rock shaft and the various detents, means for moving any selected one of the clutch controlling levers to close the respective clutch and open the duct closing valve of the player unit, and means actuated 50 by the movement of any one of the clutch controlling levers for rotating the rock shaft and moving the detents to release the clutch controlling levers of the other player units.

19. A piano player mechanism including 55 a series of independent player units each of which is provided with its own music sheet and duct bridge, normally closed duct closing valves for the duct bridges, independent driving elements for the player units, nor- 60 mally inoperative clutches controlling the driving elements, levers having operative connections with the clutches and formed with lateral arms, operative connections between the said lateral arms of the le-

vers and the duct closing valves, detents 65 for holding the levers in operative position, selective means for moving any one of the levers into operative position to close the corresponding clutch and open the duct closing valve of the particular 70 player unit, and means actuated by the movements of any one of the clutch controlling levers for releasing the detents of the clutch controlling levers of the other player units. 75

20. A piano player mechanism including a series of independent player units each of which is provided with its own music sheet and duct bridge, independent driving elements for the player units, normally inoperative 80 clutches controlling the driving elements, normally closed duct closing valves for the duct bridges, levers controlling the duct closing valves, clutch controlling levers having operative connection with the 85 clutches, operative connections between the clutch controlling levers and the duct valve controlling levers, and means for actuating any selected one of the clutch controlling levers. 90

21. A piano player mechanism including a series of independent player units each of which is provided with its own music sheet and duct bridge, independent driving elements for the player units, normally inoperative 95 clutches controlling the driving elements, clutch controlling levers having an operative connection with the clutches, normally closed duct closing valves for the duct bridges, levers controlling the duct closing 100 valves, operative connections between the said levers and the corresponding clutch controlling levers, detents for engaging the clutch controlling levers to hold the same in operative position, means for actuating any 105 selected one of the clutch controlling levers, and means actuated by the movement of any one of the clutch controlling levers for releasing the detents of all of the remaining clutch controlling levers. 110

22. A piano player mechanism including a series of independent player units in operative position at all times each of which is provided with its own note sheet and duct bridge, independent pneumatics for the various 115 player units, means actuated by each of the pneumatics for throwing the particular player unit into action and shutting off any of the other player units which may have been previously in action, and selective 120 means for controlling the pneumatics.

23. A piano player mechanism including a series of independent player units, independent pneumatics for the various player units, means actuated by each of the pneumatics for throwing the particular player unit into action and rendering all of the other player units inoperative, individual 125

pipes leading to the pneumatics, valves for the said individual pipes, and selective means for controlling the said valves.

24. A piano player mechanism including
5 a series of independent player units, independent pneumatics for the various player units, means actuated by each of the pneumatics for throwing the particular player unit into action and rendering all of the
10 other player units inoperative, individual

pipes leading to the pneumatics, valves for the individual pipes, electro-magnets controlling the valves, and selective means for energizing the electro-magnets.

In testimony whereof I hereunto affix my 15
signature in the presence of two witnesses.

FRED R. GOOLMAN.
